DRAFTING INSTRUMENT

Ralph Allison Hendry, Truro, Nova Scotia,
Canada

Application August 30, 1944, Serial No. 551,893

3 Claims. (Cl. 33—27)

1

My invention relates to improvements in drafting instruments, the primary object in view being to provide a device of simple form and inexpensive construction especially adapted for measuring angles, plotting curves, particularly railway and highway curves, and performing all the functions of a set of conventional curves.

Ancillary objects are also comprehended by my invention, all of which, together with the precise nature of my improvements, will be readily understood when the succeeding description and claims are read with reference to the drawing accompanying and forming part of this application.

In said drawing:

Figure 1 is a view in plan of my improved instrument in the preferred embodiment thereof,

Figure 2 is a view in edge elevation,

Figure 3 is a view in rear elevation drawn to an enlarged scale,

Figure 4 is a view in plan of the bushing and anchor block,

Figure 5 is a view in vertical section taken on the line 5—5 of Figure 4, and

Figure 6 is a view in perspective of the anchor block.

Referring to the drawing by numerals, my improved instrument, as illustrated, comprises a protractor-like body 1 of substantially 90° segmental form and of transparent material, such as Celluloid, and which is provided with straight side edges 2, and a tail tab 3 having an axis-forming aperture 4 therein surrounded, on the upper face of the tab 3, by a bushing 5 registering with said aperture 4 and suitably secured on the tab. The face of the body 1 is provided with two 90° radius lines 6, 7 along said edges 2, a 45° radius line 8, arcuate lines 9 of different radii, and tangent lines 10 for each arcuate line 9 drawn at the intersection of each line 9 with radius line 8. The circumferential edge of the body 1 is graduated in degrees from the 45° radius line 8 to the 90° radius lines 6, 7, as shown at 10'. Holes 11 are drilled in the body 1 at the extremities of the tangent lines 10, and similar holes at the approximate points of intersection of the arcuate lines 9 and the radius lines 6, 7.

A cylindrical, axially bored anchor block 13, higher than the bushing 5 for a purpose presently seen, is provided for fitting in the bushing 5, and a pointed center pin 14 for fitting in the bore of the anchor block 13. A pair of angularly spaced, bottom anchor pins 15 are provided on the anchor block 13.

In the use and operation of the described in- 55

strument, the center pin 14 is first placed in the anchor block 13 and with the block held canted on a work sheet, or the like, so that the point of the pin 14 is visible beneath the block, said pin 5 is centered on a selected center point, the block and pin then straightened up so that the anchor pins 15 can be forced into the work to hold the anchor block 13 on center, and the bushing 5 is then slipped over the anchor block 13 so that the body 1 may be swung about the centered anchor block 14 flat on the work.

The arcuate lines 9 are designated by suitable degree and minute markings indicating the degree of curve of the arcs to a predetermined scale 15 as shown in Figure 1.

It is not believed to be essential to a proper understanding of the invention to describe all possible uses of the same. The uses described in the following are deemed sufficient.

20 To lay off an angle from a given point on tangent, the term "tangent" meaning any straight portion of a center line, following railway and highway practice, center the anchor block 13 on the given point and anchor said block on center, 25 in the manner already described. Rotate the body 1 so that one or the other of the radius lines 6, 7, 8 lies along the tangent. Then lay off angles as ordinarily done with a protractor.

To draw a circle, anchor the anchor block on a given center, place a pencil in one of the holes 12 of the arcuate line corresponding to the radius of the curve desired, and allow the pencil to push the body 1 around until the circle is completed.

Other uses of the instrument will be apparent. The foregoing will, it is believed, suffice to impart a clear understanding of my invention without further explanation.

Manifestly, the invention as described, is susceptible of modification without departing from the inventive concept, and right is herein reserved to such modifications as fall within the scope of the appended claims.

What I claim is:

1. In an instrument of the class described, a transparent body of substantially ninety degree segmental form provided with an apertured axis-forming tab, a bushing fixed on said tab concentrically of the aperture in the tab, an anchor block fitting in said bushing and adapted to form a bearing about which the bushing and body may be rotated on a piece of work, means to center said anchor block relative to a selected point on the work, and means on said block to attach the same to the work in centered position.
2. In an instrument of the class described, a

transparent body of substantially ninety degree segmental form provided with an apertured axis-forming tab, a bushing fixed on said tab concentrically of the aperture in the tab, an anchor block fitting in said bushing and adapted to form a bearing about which the bushing and body may be rotated on a piece of work, means to center said anchor block relative to a selected point on the work, and means on said block to attach the same to the work in centered position, the first-mentioned means comprising a centering pin, said block having an axial bore extending therethrough through which the pin is adapted to be extended.

3. In an instrument of the class described, a transparent body of substantially ninety degree segmental form provided with an apertured axis-forming tab, a bushing fixed on said tab concentrically of the aperture in the tab, an anchor

block fitting in said bushing and adapted to form a bearing about which the bushing and body may be rotated on a piece of work, means to center said anchor block relative to a selected point on the work, and means on said block to attach the same to the work in centered position, the last-mentioned means comprising bottom pins on the block adapted to be forced into the work.

RALPH A. HENDRY.
